No. 839,513.

PATENTED DEC. 25, 1906.

C. A. ROLFE.
ELECTRIC CIRCUIT PROTECTOR.
APPLICATION FILED DEC. 3, 1900.

Charles A. Rolfe,
by Charles A. Brown & Clegg, Atty.

UNITED STATES PATENT OFFICE.

CHARLES A. ROLFE, OF CHICAGO, ILLINOIS, ASSIGNOR, BY MESNE ASSIGNMENTS, TO ROLFE ELECTRIC CO., OF ROCHESTER, NEW YORK, A CORPORATION OF NEW YORK.

ELECTRIC-CIRCUIT PROTECTOR.

No. 839,513.

Specification of Letters Patent.

Patented Dec. 25, 1906.

Application filed December 3, 1900. Serial No. 38,437.

To all whom it may concern:

Be it known that I, CHARLES A. ROLFE, a citizen of the United States, residing at Chicago, in the county of Cook and State of Illinois, have invented a certain new and useful Improvement in Electric-Circuit Protectors, (Case 4,) of which the following is a full, clear, concise, and exact description, reference being had to the accompanying drawings, forming a part of this specification.

My invention relates to protectors for protecting low-tension instruments and circuits from injury by the intrusion of unduly strong currents, such as power and lighting currents.

The invention relates in particular to a variety of such electrical protectors in which is employed a body or mass of material which may be said to be softenable or fusible—that is to say, sufficiently responsive or susceptible to a moderate degree of heat to cause it to be softened or fused by the application of such an amount of heat. In certain forms of this style of protector the fusible or softenable material consists of wax. In others it consists of solder. Various kinds of wax have been employed, as have also various kinds of solder, the composition of each being sufficiently varied to cause them to be properly responsive to heat of any desired moderate degree and enduring for any desired moderate length of time. In these protectors the operation of the device is permitted by the fusing or softening of the mass or body of fusible or softenable material, and to such end the devices are each provided with a device for concentrating heat, so that it shall be applied to the said mass or body of material and also with a circuit-controlling device or set of devices by which the circuit is controlled in any desired way by the fusion or softening of said body of material.

The heat-concentrating devices and the circuit-controlling devices have varied very largely in different forms of protectors. In most instances the heat-concentrating device has consisted of a coil of fine wire which would become heated, and so form a heated mass or ball upon the passage of an unduly strong current through the wire. This coil of fine wire has been so associated with the mass or body of fusible or softenable mate-

rial that when the coil has become heated by the unduly strong current the body or mass of fusible or softenable material has been fused or softened. In certain of such devices the heat-concentrating coil has been embedded within the mass or body of material, while in others the coil has been arranged outside of or surrounding the said mass or body. In either case, however, the association has been so close that the generation of a moderate degree of heat in the coil has affected the mass or body of fusible or softenable material.

The circuit-controlling devices have usually consisted of suitable mechanisms by which the circuit is opened upon the softening or fusing of the fusible or softenable material, although in certain instances these circuit-controlling devices have been such as to cause the circuit to be shunted to ground instead of being opened. In either case the arrangement is such that when an unduly strong current traverses the heat-concentrating device and causes the generation of a sufficient amount of heat to affect the mass or body of fusible or softenable material the circuit-controlling device operates. In the one case the circuit is opened and in the other case it is shunted to ground. In both cases, the instrument on the circuit and the circuit itself are protected from the unduly strong current—in the first instance by the complete stoppage of the current and in the second by its diversion from the circuit and instrument under protection to another circuit.

As an example of a protector of the class mentioned I might cite that described, illustrated, and claimed in the patent to Albert Barrett, No. 445,217, of January 27, 1891, for a thermal cut-out. In this patent the heat-susceptible device consists of a ball or button of wax, and the heat-concentrating mass consists of a coil of wire which is embedded within the material of the wax. The coil of wire surrounds the end of a loop or shank, and a spring is arranged and held under tension by this loop or shank. The ball or button of wax is held against the operation of the spring by a suitable support or abutment. The operation of the device, then, is that when an unduly strong current intrudes upon the line the coil of wire gener-

ates sufficient heat to cause the portion of the wax ball or button immediately surrounding it to soften. The spring is thereby released and operates so as to withdraw the end of the 5 loop, with the coil surrounding it, from the interior of the ball or button of wax. By such withdrawal and by the continued movement of the coil and loop as they are 10 acted upon by the spring the ends of the coil are ruptured, so as to break or open the circuit.

The invention of the present application relates in particular to the heat-concentrating device by which the heat-susceptible 15 body or mass is affected; and its object is to provide the simplest possible and least expensive form of device of this kind and at the same time to dispense entirely with the use 20 of conducting-wires for such device and the attendant inconveniences thereof.

In carrying out my present invention I employ as a heat-concentrating device a conductor having a high specific resistance. The substance now most suitable, so far as I 25 am at present aware, is high-resistance graphite—such, for example, as is at present employed in ordinary lead-pencils. This substance has a very high specific resistance, so that the mere passage of even moderate 30 currents through it results in its being rapidly heated through its own internal resistance, the connections to it, it being understood, being good, so that the only effective resistance is the internal resistance of the 35 graphite. By actual experimentation I have found that a short length of graphite of this kind will generate sufficient heat to operate the protector upon the passage of very small currents. In fact, by the use of graphite in 40 this way the device can be made as sensitive and as accurate and reliable in operation as could heretofore be done with a coil of fine wire. By the use of such a material of high specific resistance sufficient heat can be secured in a short rod or stick thereof without 45 forming a coil of the same, and thus self-induction is avoided and a protective device with a non-inductive resistance is provided. At the same time the expense of manufacture 50 is greatly reduced, and the device is simpler. This non-metallic substance, such as carbon, can be combined or associated or united with the heat-susceptible body or mass in any desired or preferred or well-known manner. 55 For the purpose of illustrating its use I have shown it embodied in the form of protector which I have shown, described, and claimed in applications filed by me on January 11, 1897, Serial Nos. 618,795 and 618,796, and have 60 also shown it embodied in the form of protector patented August 13, 1895, to Frank R. McBerty. Although I consider both of these forms of protective devices when containing the improvement of this application to be 65 exceedingly satisfactory and advantageous,

I do not desire to be limited to them in the broader feature of the invention, for I consider that this broader feature can be embodied in any style or form of protector which is now or may hereafter be constructed. 70

In the accompanying drawings, Figure 1 is a side elevation of a protector embodying my present invention, the said protector being in general arrangement that referred to as shown and described in my said applications, Serial Nos. 618,795 and 618,796. Fig. 2 is an end elevation of the same. Fig. 3 is a vertical section of a structure in which the heat-concentrating and heat-susceptible masses or bodies are associated as used in the 80 protector shown in Figs. 1 and 2. Figs. 4 and 5 are views corresponding to Figs. 1 and 2 of a modified form of protector embodying my invention, this protector being in general arrangement that referred to as shown and 85 described in said patent to McBerty, No. 544,368. Fig. 6 is a vertical section corresponding to Fig. 3 of the structure, in which are combined the heat-generating device and the heat responsive or susceptible mass or 90 body of material as employed in the protector shown in Figs. 4 and 5.

Referring first to the form of protector shown in Figs. 1, 2, and 3, it will be seen that this protector comprises an insulating-base 95 A and a pair of circuit-breaking devices B B. The two circuit-breaking devices B B are intended for the opposite sides of the circuit to be protected. For their accommodation the base A is provided with two pairs of 100 sockets 1 1, which are connected with suitable terminal wires 2 2, whereby each of the circuit-breaking devices B B can be included in the circuit.

The devices B B are desirably exactly the 105 same in construction, so that a description of one of them will answer for both. Each one comprises a pair of metal rods 3 3, whose lower ends are adapted to fit into the sockets 1 1 of the base A; a top cross-piece 4, rigidly secured to the upper ends of the rods 3 3; a lower cross-piece 5, which is arranged loosely upon the lower portions of the rods 3 3; a pair of coiled springs 6 6, which inclose the 110 portion of the rods 3 3 between the cross-pieces 4 and 5 and tend normally to separate said cross-pieces from one another. The springs 6 6 are held in tension, or, in other words, the cross-pieces 4 and 5 are held 115 against separation by a hook or link 7, which is secured to the lower cross-piece 5, and a releasing device C, Fig. 3, which includes in its construction the heat generating or concentrating and the heat-susceptible devices. The device C illustrated consists 120 of an outer metallic shell 8 and an inner metallic shell 9, whose lower end is embedded or inclosed within the outer shell 8 and whose upper end is expanded or flared, so as to be appreciably larger than the outer shell 8. 125

The lower portions of the inner shell 9 and the outer shell 8 are held normally firmly together by a layer 10 of solder, which is interposed between the same. The solder composing this layer 10 is obviously a heat-susceptible device formed of the fusible or softenable material which can be affected by the heat concentrated by a heat-concentrating device. In the interior of the shell 9 is arranged a plug 11, having a central bore in which is arranged a small stick or piece 13 of common graphite—such as is used, for example, in lead-pencils. The plug 11 is made of insulating material—such, for example, as vulcanite or hard rubber. The lower end of the carbon rests upon the bottom of the inner shell 9. The stick of graphite 13 extends up above the top of the plug 11. The releasing device C thus constructed is inserted in an opening in the upper cross-piece 4 of the circuit-breaking device B, this opening being sufficiently large to receive the shell 8 but too small to receive the flaring or expanded end of the inner shell 9. In this way the device C serves as an anchor for the link 7, the outer shell 8 being conveniently provided with an eye adapted to receive the upper end of the link 7. When thus mounted in the circuit-breaking device B, a metallic strip 14 is held by suitable thumb-screws at the top of one of the rods 3 and extended across from that rod, so as to rest upon the top of the graphite stick 13. The strip 14 serves not only to make connection between the rod 3 and the stick 13, but also serves to hold the stick 13 against the bottom of the inner shell 9. Another metallic strip 15 is extended from the other rod 3 to the device C and is conveniently arranged below the outwardly-flaring part of the inner shell 9, this strip 15 being also connected with the rod 3 by suitable binding-screws thereon. In this way the circuit is closed through each circuit-breaking device B by means of the rods 3, the strips 14 and 15, the graphite stick 13, and the inner shell 9.

The operation of the device is as follows: When an unduly strong current passes through the circuit, the carbon stick 13 is heated thereby to such an extent as to cause the solder 10 to become softened. As soon as it is softened the shell 8 is free to leave the inner shell 9, and consequently the springs 6, 6 are free to operate. They therefore operate, and in so doing they force the cross-piece 4 rapidly upward, thereby withdrawing the rods 3, 3 from the sockets 1, 1 in the base A. The impetus given to the cross-piece 4 is so great that the whole device B springs bodily away from the base A a considerable distance, thereby justifying the name "jump-out," which is commonly employed for this general form of circuit-breaking device. When one of the circuit-breaking devices B is thus ejected or thus jumps out, a

wide gap is opened in the circuit by the withdrawal of the rods 3, 3 from their sockets 1, 1.

The form of protector illustrated in Figs. 4, 5, and 6 comprises a base A' and a pair of circuit-breaking devices, one for each side of the circuit. Each of these circuit-breaking devices consists of a standard 16, a spring 17, and a releasing device C', supported by said spring and standard and engaged with the upper ends thereof. The releasing device C', as well shown in Fig. 6, consists of a cylinder 18, composed of insulating material, preferably hard rubber or vulcanite; a graphite stick 19, preferably similar in composition to the graphite stick 13, previously referred to; a plug 20 screwed into one end of the cylinder 18 and a plug 21 screwed into the other end. The plug 21 is provided with a flaring socket-shaped end 21^a, and into this is fitted the correspondingly-shaped nose 22^a of a plug 22, the nose 22^a and flaring socket 21^a being secured to one another by a layer 23 of solder adapted to be softened by a moderate degree of heat. The plugs 20 and 22 are formed with annular recesses, which can be inserted in suitable slots formed in the top of the standard 16 and spring 17, whereby the device C' can be held and engaged by said standard and spring.

The operation of this device is as follows: As in the case of the form of protector described before, the passage of an unduly strong current heats the graphite stick 19, and in the present form this heat is conveyed to the layer 23 of solder, so that this solder is softened or fused. When thus softened or fused, the flaring end 21^a of the plug 21 and the end 22^a of the plug 22 are free to separate and they are instantaneously drawn apart from one another by the action of the spring 17. In this way the circuit is opened by the separation of these two conducting members, it being understood, of course, that the circuit is made through the standard 16 and spring 17.

As previously stated, these different devices will serve to illustrate the various ways in which my present invention can be employed; but I do not by any means consider these the only applications which can be made of the invention. It will be seen that a protector embodying my present invention, whether it be of the kind illustrated and described here or not, possesses many desirable features, among which are simplicity of construction, cheapness of manufacture, and the dispensing with all wires.

By "material of high specific resistance," as used herein, I mean materials such as graphite, carbon, and the like, whose specific resistance is so great, as compared with that of the metals silver, copper, zinc, iron, and the like, that they are not used commercially as electrical conductors and are not, in fact,

what are considered generally as good conductors. For instance, the specific resistance of silver is .77 and for the other metals it is greater, extending up to 64.52 for bis-
 5 muth. The specific resistance of graphite, on the other hand, is given by a good authority as 1106 and that of gas-carbon as 2037. It will be seen that the metals form a group whose specific resistances do not differ greatly
 10 from one another as compared with the specific resistances of graphite and gas-carbon. Hence it will be seen that the latter materials can be considered high specific-resistance conductors as compared with the metallic conductors, and it is such materials that I intend
 15 to designate by the term "high-resistance conductors," it being seen that the entire group of metals, even including the metals antimony, mercury, and bismuth, ordinarily
 20 considered high-resistance conductors, are, as compared with graphite, carbon, and the like, of low specific resistance.

What I claim as my invention is—

1. In a protector, the combination of inner and outer shells or casings, the outer one inclosing the inner one, a layer of material susceptible to a moderate degree of heat arranged between said shells or casings and adapted to secure the same together, and a
 25 heat-concentrating device confined within the inner shell.
2. In a protector, the combination of an inner shell and an outer shell inclosing the inner shell, a layer of solder interposed between said shells and adapted to secure the same together, and a stick or body of high-resistance graphite arranged and confined within the inner shell and associated therewith so that the heat generated by the graphite will act to melt or soften the solder.
 35
3. In a protector, the combination of inner and outer shells or casings, the former inclosed within the latter and provided with an expanded or enlarged upper part, an insulating-plug arranged within the inner shell, a layer of solder uniting the shells, and a graphite stick arranged within a bore formed in said insulating-plug, substantially as set forth.
 45
4. In a protector, the combination of inner and outer shells, the inner shell being provided with an enlarged upper portion and the outer shell being constructed with a projection having an eye or aperture, a layer of solder uniting the shells, a plug composed of insulating material arranged within the inner shell, and a stick of graphite arranged within the bore formed in the said insulating-plug, substantially as described.
 55
5. In a protector, the combination with a

base having sockets, of a circuit-breaking device comprising a pair of metallic rods adapted to fit in the said sockets of the base, an upper cross-piece fixed upon said rods, a lower cross-piece fitted loosely on said rods, a pair of springs interposed between said cross-pieces and tending to separate the same, a releasing device comprising a couple of separable members, a mass of solder or like material interposed between said members and adapted to hold the same together, a body or stick of carbon or like material associated with one of said members so that the heat generated by the carbon will fuse or soften the solder or like material, the said releasing device being engaged by the upper cross-piece, a link connecting the releasing device and the lower cross-piece and electrical connections whereby the said body or stick of carbon or the like is included in the circuit.
 65

6. In a protector, the combination with a base having a pair of sockets, of a circuit-breaking device consisting of a pair of metallic rods adapted to fit in said sockets, an upper cross-piece rigidly secured to the upper ends of said rods, a lower cross-piece arranged to slide upon the lower portions of the same, a pair of springs interposed between said cross-pieces and tending normally to separate the same, a releasing device consisting of inner and outer metallic shells, the inner shell having an enlarged upper end, a layer of solder interposed between said shells and adapted to hold the same normally together, a stick or body of carbon arranged within the inner shell, a plug of insulating material also arranged within the inner shell and serving to hold the carbon in position, the said releasing device being arranged in an aperture in the upper cross-piece so that the enlarged portion of the inner shell of said device engages the said cross-piece, a link engaging the outer shell of the releasing device and secured to the lower loosely-mounted cross-piece, a conductor connecting one of said metallic rods with one of the shells of the releasing device, and a metallic strip extended from the other rod over to the top of the carbon in the plug of the releasing device and arranged upon said carbon so as to make contact therewith and force the carbon against the bottom of the shell, substantially as described.
 85

In witness whereof I hereunto subscribe my name this 28th day of November, A. D. 1900.

CHARLES A. ROLFE.
